PUMP AND COMPRESSOR

John Adrian Chamier, Aldwych, London, and
George Frederick Jones, West Hill, Highgate,
London, England

Application March 16, 1937, Serial No. 131,244

9 Claims. (Cl. 103—162)

This invention has reference to pumps and compressors comprising two cylinder blocks rotatably mounted at an angle to each other with an end of each block adjacent to an end of the other and with angular pistons arranged one end of each piston in a cylinder in one block and the other end in a cylinder in the other block.

Such pumps and compressors are desirable because they give substantially continuous output in spite of using reciprocating pistons and one object of the present invention is to provide an improved construction of a pump or compressor according to the above wherein the driving force is directly applied to both blocks as distinct from being applied to one block and transmitted to the other through bevel gearing or through the pistons.

A further object of the invention is to provide in the pump or compressor an improved construction of worm gear wherein the thrust of a worm on the worm wheels for effecting the direct driving of the rotary blocks has no longitudinal turning moment about the bearings supporting the wheels.

Another object of the invention is the provision of an improved construction of pump or compressor as set forth above wherein bearings for the rotary blocks, valve plates and head blocks are secured to a casing by easily accessible bolts common to these elements.

A still further object of the invention is the provision in the pump or compressor of valve plates which, in addition to their function as such, act as spacers or shims ensuring an exactly correct tolerance between themselves and the head end of the rotary blocks in contact with them.

Further, an object of the invention is to provide an improved mounting for the rotary blocks whereby the valve plates at the head ends prevent outward displacement of the blocks with respect to the pump or compressor casing whilst appropriately fashioned surfaces at the other or adjacent ends of the blocks prevent inward movement of the said blocks.

The above and other objects of the invention will be clear from the accompanying drawings taken in conjunction with the following description.

50 In the said drawings:

Fig. 1 is a side elevation, mainly in vertical section, of the preferred form of pump or compressor according to the invention;

Fig. 2 is a sectional elevation on the line II—II;

55 Fig. 1;

Fig. 3 is an end elevation applicable to either head block illustrated in Fig. 1;

Fig. 4 is an end view, looking from the rotary block end, applicable to either valve plate; and

Fig. 5 is a sectional elevation of the rotary block on the line V—V, Fig. 1.

In the drawings two rotary cylinder blocks 1 at right angles to each other and containing the ends of four right angled pistons 2 in their equiangularly spaced, longitudinal bores 3 are arranged within a casing 4; and valve plates 5 and head blocks 6 are located at the ends of the said casing, one plate and head being in alignment with one rotary block and the other plate and head in alignment with the remaining rotary block.

The casing consists of an upper part 7 and a tray or lower part 8 secured to the upper part by bolts and nuts 9 passing through flanges 10 on the parts 7 and 8. The casing has constricted ends 11, 11 each co-axially containing one of the rotary blocks. Annular recesses 12 are provided at the inner ends of the constrictions for the reception of flanges 13 on bearing sleeves 14.

The sleeves 14 are held in place by means of 25 bolts 15 which pass through tubular ribs 16 on the head blocks 6, through lugs 17 on the valve plates 5 and lugs 18 at the outer ends of the constrictions 11, and screw into the flanges 12 after passing through holes in the bridges 19 joining the constrictions 11 to the casing. It will thus be seen that bolts 15 provide common securing means for each set of elements 14, 5 and 6.

The worm wheels 20 are integral with and circumscribe their respective blocks and the parts as 21 of the blocks that make bearing contact with the sleeves 14. The circumscribing is effected by arranging the worm wheels at the larger ends of cones 22 extending towards the planes 40 containing the head ends of the rotary blocks.

The worm wheels and, therefore, the pump or compressor are driven by means of a worm 23 arranged in the corner between the wheels 20 at right angles to the central plane of the engine. 45 Bearing bushes 24 mounted in sockets 25 formed in the casing support the shaft 26 of the worm. One end 27 of the shaft projects well beyond the casing and is splined for co-operation with a coupling element rotated by the driving means 50 for the pump or compressor; and between this end and the worm is arranged a thrust disc 28. This disc runs between a flange 29 on the upper end of one of the bushes 24, said bush and flange being of white or bearing metal, and a dished 55

bearing plate 30 of like metal. A plate 31 clamped to the casing 4 by means of bolts and nuts 32 holds the plate 30 in place. Thrust of the worm 23 in an outward direction along its shaft 26 is taken by the plate 30 and pull or thrust in the opposite direction is taken by the flange 29, said flange 29 thrusting against part of the casing 4. A recess 33 co-axially of a centric boss 34 through which the outer end of the shaft 26 passes receives a packing box 35 that prevents escape of lubricant from the interior of the casing 4.

The outer or head ends of the rotary blocks have ports 36 to enable fluid to flow into and out of the cylinder bores 3. During the working of the pump or compressor ports 36 register first with one opening 37 in a valve plate and then with the other opening. The valve plates bear against the outer or head ends of their respective rotary blocks and each has an annular flange 38 which surrounds the unreduced end 39 of a block to provide a second bearing therefor. The flanges 38 fit closely in their constrictions 11 so as to receive stability from the casing.

Owing to the worm wheels 20 circumscribing the rotary blocks in planes between the end bearing surfaces at 21 and 39 the worm wheel 23 does not tend to tilt the blocks on their longitudinal axes i. e., the thrust of the worm wheel has no turning moment about the bearings along the longitudinal axes of the rotary blocks.

The valve plates 5 prevent outward movement of the blocks with respect to the casing and the conical surfaces of the cones 22 are in rolling contact at the corner of the angle so that the rotary blocks cannot move inwardly. The exact degree of tolerance is determined by the thickness of the plates 5 between the lugs 18 on the casing and the lugs 16 on the head: the more this thickness is reduced from the sides in contact with the lugs 18 the more the middle parts of the plates project into the constrictions 11 and the closer these parts come to the outer ends of the rotary blocks.

Each head block is substantially in the form of a hollow cylinder closed at its outer end 40 and divided into two symmetrical compartments 41 by a vertical partition 42. The partition has a central circular flange 43 which, in addition to holding the plate 5 up to the outer end of its rotary block, provides two arcuate openings 44 in register with the openings 37 in a valve plate 5. Rectilinear protuberances 45 at one side of each head block are provided with two holes 46 communicating one with one compartment 41 and one with the other compartment whilst both are screw-threaded for the reception of unions connecting supply and outflow pipes to the head.

When the worm 23 is rotated it turns the blocks 21 in synchronism and the pistons 2 are carried round by the blocks with the result that they reciprocate. One compartment 41 in one head block 6 and the corresponding compartment in the other head block receive fluid from the supply pipe and allow it to pass through corresponding openings 44 and 37 and through ports 36 into bores 3, the fluid so flowing owing to the suction created by those pistons moving away from the head ends of the blocks. When the said pistons move towards the head ends they discharge the fluid through ports 36, through the other openings 37 and the openings 44 into the remaining compartments 41, said fluid passing from thence through outflow pipes. If the worm 23 is driven in the opposite direction the fluid flow is reversed.

What we claim is:—

1. In a pump or compressor comprising two cylinder blocks rotatably mounted at an angle to each other with an end of each block adjacent to an end of the other and with angular pistons 5 arranged one end of each piston in a cylinder in one block and the other end in a cylinder in the other block, a drive directly applied to said cylinder blocks comprising two worm wheels around the said blocks near the said adjacent ends and having a rolling contact in the acute angle formed by the blocks and a single driving worm in mesh with both worm wheels in line with the rolling contact between the said wheels. 10

2. In a pump or compressor according to claim 15 1, bearing elements around the blocks near the said adjacent ends, bearing elements around the opposite ends of the said blocks, the said worm wheels circumscribing the said blocks, the centre planes of said wheels lying between said bearing 20 elements whereby the thrust of said worm on said blocks has no longitudinal turning moment about the said bearings.

3. In a pump or compressor as defined in claim 1, wherein the rotary cylinder blocks are each 25 provided with a conical end, with the said ends in rolling contact with each other, and wherein the said worm wheels are rigid with said conical end and circumscribe the cylinder blocks, with bearing elements around said blocks adjacent the 30 conical ends thereof, and bearing elements around the cylinder blocks at the ends remote from the conical ends.

4. A pump or compressor as defined in claim 1, wherein the said rotary cylinder blocks are 35 each provided with a conical end, with the said ends making rolling contact with each other, the conical end of each block inclining outwardly from the inner terminal of the block, the said worm wheels being rigid with the conical ends of 40 the cylinder blocks substantially in the plane of the maximum diameter of said conical ends, together with bearing elements around the cylinder blocks between said blocks and said worm wheels, and bearing elements for the cylinder blocks at 45 the ends of said blocks remote from the conical ends.

5. In a pump or compressor according to claim 1, a casing containing said cylinder blocks and said pistons, a bearing sleeve at the inner face 50 of one side of said casing and a bearing sleeve at the inner face of a side at right angles thereto, said sleeves surrounding the cylinder blocks near the said adjacent ends thereof, a valve plate at the outer face of each side, head blocks on 55 the outer faces of said valve plates, and bolts passing through said head blocks, said valve plates and said sides of the casing and screwing into said bearing sleeves to secure the sleeves, valve plates and head blocks in position on the casing. 60

6. In a pump or compressor according to claim 1, a casing containing said cylinder blocks and said pistons, a constriction at one side of said casing and a constriction at the side at right angles thereto, a bearing sleeve at the inner end 65 of each constriction, said sleeves surrounding the cylinder blocks near the said adjacent ends thereof, a valve plate at the outer end of each constriction, head blocks on the outer faces of said valve plates, and bolts passing through said head blocks and through said valve plates, extending along said constrictions and screwing into said bearing sleeves to secure the sleeves, valve plates and head blocks in position on the casing. 70

7. In a pump or compressor according to claim 75

1, a casing containing said cylinder blocks and said pistons, a constriction at one side of said casing and a constriction at the side at right angles thereto, a bearing sleeve at the inner end of each constriction, said sleeves surrounding the cylinder blocks near the said adjacent ends thereof, valve plates at the outer ends of the constrictions, an annular flange on each valve plate closely fitting into each constriction, the outer ends of said cylinder blocks entering said flanges to be borne thereby, head blocks on the outer faces of said valve plates, and bolts passing through said head blocks and through said valve plates, extending along said constrictions and screwing into said bearing sleeves to secure the sleeves, valve plates and head blocks in position on the casing.

8. In a pump or compressor according to claim

1, a casing, said blocks being mounted at right angles to each other in said casing with their outer ends adjacent to the sides of the casing, a valve plate at these sides and means for clamping said valve plates in position at peripheral portions thereof whereby clearance between said valve plates and the ends of said blocks can be exactly set by alterations in the effective thickness of said peripheral portions of the valve plates.

9. In a pump or compressor according to claim 1, a casing of right angled form, bearing sockets in the angle of said casing at right angles to the central plane of the pump or compressor, bearing bushes in said sockets, and a shaft borne by said bushes, the said worm cooperating with the said worm wheels being carried on said shaft.
